UNITED STATES PATENT OFFICE

167,482

TOY SIREN OR THE LIKE

Carl Rosini, Flushing, N. Y.

Application April 1, 1952, Serial No. 19,141

Term of patent 7 years

(Cl. D34—15)

To all whom it may concern:

Be it known that I, Carl Rosini, a citizen of the United States and a resident of Flushing county of Queens, and State of New York, have invented a new, original, and ornamental Design for Toy Siren or the like, of which the following is a specification, reference being had to the accompanying drawing, forming part thereof.

I claim:

The ornamental design for a toy siren or the like, substantially as shown.

CARL ROSINI.
